Primary Examiner—Stacia Cadmus(74) *Attorney, Agent, or Firm*—Oliff & Berridge, PLC(57) **CLAIM**

The ornamental design for a rear wing for an automobile, as shown and described.

DESCRIPTION

FIG. 1 is a perspective view of a rear wing for an automobile, the perspective view taken from in front of and above the wing;

FIG. 2 is a rear view thereof, taken from a rear of an automobile;

FIG. 3 is a front view thereof, taken from a front of an automobile;

FIG. 4 is a top view thereof;

FIG. 5 is a bottom view thereof;

The broken line showing of an automobile is for illustrative purposes only and forms no part of the claimed design.

1 Claim, 4 Drawing Sheets**OTHER PUBLICATIONS**

FIG. 6 is an end view thereof, taken from a side of an automobile, the opposite end view being a mirror image; and,
FIG. 7 is a perspective view thereof attached to an automobile.
